FRANK M. LEAVITT, OF SMITHTOWN, NEW YORK, ASSIGNOR TO E. W. BLISS COMPANY, OF BROOKLYN, NEW YORK, A CORPORATION OF WEST VIRGINIA.

GYROSCOPIC STEERING MECHANISM.

1,197,134.

Specification of Letters Patent. Patented Sept. 5, 1916.

Application filed November 2, 1915. Serial No. 59,166.

To all whom it may concern:

Be it known that I, FRANK M. LEAVITT, a citizen of the United States, residing in Smithtown, in the county of Suffolk and 5 State of New York, have invented certain new and useful Improvements in Gyroscopic Steering Mechanism, of which the following is a specification.

This invention relates to gyroscopic mechanism for steering automobile torpedoes or other analogous vessels. In such mechanisms the engine or other steering mechanism which operates the rudder or other steering element is controlled in its operation by the directive effect of a gyroscope. In the earlier mechanisms the gyroscope directly operated a valve or other means for controlling the steering mechanism; this however involved the disadvantage that the 20 resistance to movement of such valve, although slight, was sufficient to throw upon the gyroscope an appreciable amount of work such as to impair its effective operation. To remedy this defect the more successful devices of this character have been 25 provided with controlling means whereby the angular position of the gyroscope relatively to the torpedo exercises the requisite control over the steering mechanism without any appreciable reaction being exerted 30 against the gyroscope; the means for this purpose used in the Bliss-Leavitt torpedo has comprised a tappet device the control of which by the gyroscope is so sensitive as to 35 practically eliminate any reaction against the gyroscope. Another system for accomplishing the same purpose is that set forth in the patent to F. W. Dodd, granted October 12, 1915, No. 1,156,350, wherein the gyroscope controls the direction of an air jet, and the steering mechanism is actuated by 40 a jet-operated means driven by such air jet.

The present invention provides an improved mechanism operating upon the air jet principle.

The invention aims to provide an extremely simple control mechanism which shall be thoroughly reliable and efficient.

It further provides means for effecting 50 angular control of the steering direction before the launching of the torpedo, in order to give the latter what is known technically as a "curved fire" whereby the torpedo when launched in one direction may 55 be caused to steer through a curved path

covering a predetermined angle, and thereafter to steer a generally straight course toward its destined target.

In the accompanying drawings,—Figure 1 is a side elevation of the preferred form 60 of steering mechanism according to the present invention, the view being partly in vertical section in a plane longitudinally of the torpedo and through the center of the gyroscope; Fig. 2 is a plan of the mechanism partly broken away; Fig. 3 is a fragmentary plan of the gyroscope alone; Fig. 4 is a vertical section showing the gyroscope turned at right angles to the position shown in Fig. 1; Fig. 5 is a sectional 70 plan of the gyroscope base, the plane of the section being indicated by the line 5—5 in Fig. 4. Figs. 6 and 7 are enlarged sections of a part of Fig. 1; Fig. 8 is a sectional elevation of a detail; Fig. 9 is a vertical 75 mid-section of a modified construction.

In the drawings an air-spun gyroscope is shown of the type employed in the Bliss-Leavitt torpedo, and the steering mechanism is an air-driven engine or servo-motor; but 80 neither of these is essential to the present invention, it being admissible to use any suitable means for spinning up the gyroscope, and any suitable means for operating the rudder or other steering element.

Referring to the drawings, A designates the steering mechanism, here shown as an engine or servo-motor driven by air admitted at a to a valve chest b containing a valve which is operated by a stem c, all as 85 usual, while the engine cylinder contains a piston or plunger the rod B of which passes out through the aft end and is connected by a coupling d to the tiller rod leading aft to control the rudder in the usual manner.

C is the gyroscope, which is usually of the construction comprising a fly-wheel e hung in an inner gimbal f standing normally horizontal, and hung in turn in an outer gimbal g standing normally vertical, and which turns around a vertical axis by means of ball bearings or other pivotal connection with a supporting frame D which may be variously constructed, the particular construction shown comprising an outer shell or 100 protecting cup E having at its upper end a head F carrying the upper pivotal bearing, and having beneath a removable head G carrying the lower pivotal bearing, the latter being shown in section in Figs. 1 and 4 110

where it is shown as a ball bearing. The upper bearing in the head F is or may be of the same construction as that here shown for the lower bearing.

5 For spinning up the gyroscope its fly-wheel axle has a pinion *h* which initially meshes with a pinion *i* on a shaft *j* turning in a sliding bushing *k*; the shaft carries on its outer end a small turbine *l* which at the 10 instant of spinning is driven by jets of air discharged obliquely from a nozzle *m* to which the air is conducted through a duct *n*, being admitted thereto under high pressure from the starting valve opened at the instant of launching the torpedo by well known 15 means, which are not here shown and require no description. During spinning the gyroscope is held stationary by a lock or bolt *o* engaging the inner ring *f* coincidentally with 20 the fly-wheel axis. After a sufficient time to spin up the fly-wheel to the required velocity, the bushing *k* is suddenly displaced to the left in Fig. 1, bringing the pinion *i* to the position shown at *i'*, where it is out of 25 mesh with the pinion *h*, and by the same movement the bolt *o* is retracted to free the gyroscope; also the turbine *l* is moved beyond the nozzle and the flow of air is shut off. The gyroscope is thus set spinning 30 with an axial direction fixed with relation to the torpedo by the bolt *o*, and fixed with relation to space by the aiming of the launching tube, all as is well understood. As 35 stated above, the spinning up means shown and described may be substituted by any other suitable means for setting the gyroscope in rotation and unlocking it.

The present invention will now be described.

40 The gyroscope carries a jet nozzle *H* which, by preference, directs the jet vertically instead of in the horizontal direction, as heretofore. Compressed air is conducted to this jet nozzle in any convenient way, as 45 for example, by taking it from a suitable source (such as the compressed air reservoir of the torpedo through the starting valve) by means of a tube *p* *p'* to a duct *q* through the lower gyroscope pivot, and by a tube *r* carried by the outer ring *g* to the nozzle. The nozzle is shown as connected to the ring *g* by means of a plate or crosshead *s* carrying on its opposite end a counterbalance *s'* to balance the weight of the nozzle 55 and the tube *r*. This plate is fastened to the ring *g* by screws passing through arc-shaped slots *t* which admit of a certain amount of angular displacement of the nozzle with relation to the gyroscope. The upward jet from the nozzle is directed against a deflecting member or disk *J* (which may be integral with the head F) which is normally stationary and which is characterized by a series of jet-deflecting surfaces formed 60 by passages or orifices *u* *u'*. These are ar-

ranged in circular order concentric with the vertical axis of rotation of the gyroscope, so that they stand in the path traversed by the jet upon any relative movement of the gyroscope with respect to the torpedo. The orifices *u* are directed obliquely in one direction, and those *u'* in the contrary direction, as best shown in Figs. 1 and 6. Between these two series is a blank space *v* which, on its underside, presents a flat face opposing the jet when the parts are in the central or neutral position, as shown in Fig. 6. When the parts are angularly diverted to either side from this position and reach the relation shown in Figs. 1 and 7, the jet 70 blows into one or other of the oblique orifices and is thereby discharged obliquely in the manner shown in Fig. 7.

75 Directly above the deflector *J* is a fan disk *K* which has fan blades in the form of radial teeth or vanes *w*, *w*, against which the obliquely directed jets of air blow. Thus the fan is revolved in one direction or the other by these air jets, according to whether they are diverted to the right or left by reason of the relative position of the jet nozzle and deflector. The fan *K* is shown as mounted on a central shaft or spindle 11 which turns in a bearing formed in a boss 12 on a cap plate or disk *L* which overlies 80 the fan *K* and which has orifices 13 for permitting the escape of the spent air.

85 The fan *K*, which constitutes a form of jet-actuated means for controlling the steering mechanism, is connected to the latter in any suitable or convenient manner. In the construction shown it has a crank connection with the valve stem *c* of the steering engine *A*. Its spindle 11 has fast to it, 90 above the hub 12, a crank head 14, the wrist pin of which engages a connecting rod 15 which is coupled to the valve stem. To make this connection adjustable the rod 15 is screw-threaded and is screwed into a threaded socket in a block 16 in which the 95 crank pin turns. A half turn of the crank displaces the engine valve for its entire throw, and thereby causes the engine to throw the rudder from hard-a-port to hard-a-starboard, or the reverse. Any further 100 turn of the crank would be futile and would produce an effect contrary to that intended; for this reason a stop is provided to limit the movement. This stop is best constructed as a pin 17 projecting from the crank head 105 14, (see Fig. 8) and which at either extreme throw strikes the rod 15 and checks any further movement, holding the fan *K* stationary, notwithstanding the impulse of the air jets tending to turn it further. The stop pin 17 thus constitutes a crank pin and has, preferably, a greater throw than that 110 of the wrist pin which engages the block 16.

115 When the torpedo swerves to either side of its true course it carries with it the de-

5 flector J, while the gyroscope holds the jet nozzle H stationary. The jet from the nozzle is thereby directed through one or other of the series of oblique deflecting perforations u or u' , and consequently turns the fan K in one direction or the other. The latter moves the valve of the steering engine, which in turn throws the rudder in such direction as to steer the torpedo back 10 toward its true course. When the torpedo has been brought back upon its precise true course the deflector and nozzle are in the relative positions shown in Fig. 6. In this position the flat under-surface of the blank 15 or neutral portion v receives the impact of the jet, so that no effect is produced. In practice, however, the torpedo is steered not merely back upon its course, but somewhat beyond, so that the jet is then directed 20 through the deflecting orifices of contrary inclination, whereby the fan K is turned in the opposite direction, which produces an opposite movement of the valve and a steering in the opposite side. Thus, the torpedo 25 is caused to steer in the usual sinuous course. If the torpedo is to run in a course in the direction in which it is launched or fired, the relative position of the nozzle and deflector at the instant of launching will be 30 that shown in Fig. 6. If, however, it is desired to cause the torpedo to steer through a curved course for a given angle and then to follow a straight course tangential thereto (or what is known technically as "curved 35 fire" or "angle fire"), the deflector J is displaced before launching through the number of degrees to right or left that the torpedo is desired to steer in its curved course before starting on its ultimate straight 40 course. For this purpose the deflector plate J is made so that it may oscillate about a vertical axis coincident with that of the gyroscope. In the construction shown it is housed within the casing E, which latter is 45 in the form of an upright cylinder concentric with the gyroscope axis; the deflector disk J may consequently be turned within this cylinder to any desired position. In the construction shown the cap plate L is 50 tightly screwed to, or otherwise engaged with, the disk J, and has external gear teeth 18 which are engaged by a worm or screw 19 carried on a shaft 20 which, as shown in the plan view, Fig. 2, extends laterally and 55 has a squared end 21 which may be engaged by a key in order to turn it. In setting the torpedo for an angle fire the operator turns this shaft 20 for a number of turns corresponding to the number of degrees of angular deflection of the course of the torpedo 60 that is desired, and to right or left as the case may be. Thus the deflector disk J is displaced to right or left to the desired angle, and it results that the torpedo, when 65 launched, will steer in a curved course until it has reached the angle thus set, whereupon its coating parts having reached the critical position shown in Fig. 6, the normal sinuous steering begins and the torpedo thereafter steers in a substantially straight 70 course.

75 It is an advantage of the construction provided by the present invention that since the fan or jet-actuated device turns around the same axis as the gyroscope, the structure 80 lends itself readily to provision for angle fire by the simple displacement of the intervening deflecting plate.

85 The invention may be variously modified without departing from its essential features. While the vertical jet is preferable, yet a radial jet, as set forth in said Dodd patent, may be substituted. Fig. 9 shows a construction in which such radial jet may be used, the nozzle H' being directed horizontally in radial direction, the deflector J' having a down-turned flange in which the deflecting orifices are formed, and the fan K' having also a down-turned flange carrying the blades or vanes and turning within a 90 downward projection from the top plate L'.

95 The invention is not limited in its application to the steering of torpedoes, but may be applied to the steering of other submersible vessels or to the steering of aeroplanes or other air-ships, or in any other location where gyroscopic steering is admissible.

100 What is claimed is:—

1. A gyroscopic steering apparatus comprising a gyroscope and steering mechanism, having means for discharging an air jet under directive control of said gyroscope, jet-actuated means operated by said jet and controlling said steering mechanism, and intervening deflecting means having a succession of oppositely inclined jet deflecting surfaces on opposite sides of a neutral point. 105

110 2. A gyroscopic steering apparatus comprising a gyroscope and steering mechanism, having means for discharging an air jet under directive control of said gyroscope, jet-actuated means operated by said jet and controlling said steering mechanism comprising a part turning around the vertical axis of the gyroscope, and intervening deflecting means having oppositely inclined jet deflecting surfaces on opposite sides of a neutral point. 115

120 3. A gyroscopic steering apparatus comprising a gyroscope and steering mechanism, having means for discharging an air jet under directive control of said gyroscope, jet-actuated means operated by said jet and controlling said steering mechanism comprising a fan rotatable around the vertical axis of the gyroscope, and intervening deflecting means having oppositely inclined jet deflecting surfaces on opposite sides of a neutral point. 125

130

4. A gyroscopic steering apparatus comprising a gyroscope and steering mechanism, having means for discharging an air jet under directive control of said gyroscope, 5 jet-actuated means operated by said jet and controlling said steering mechanism, and intervening deflecting means having oppositely inclined jet deflecting surfaces on opposite sides of a neutral point, and having 10 at such neutral point a flat face perpendicular to the direction of the jet.
5. A gyroscopic steering apparatus comprising a gyroscope and steering mechanism, having means for discharging an air jet 15 under directive control of said gyroscope, jet-actuated means operated by said jet and controlling said steering mechanism, and intervening deflecting means having a succession of orifices arranged circularly to receive such jet and inclined in opposite directions on opposite sides of a neutral point.
6. A gyroscopic steering apparatus comprising a gyroscope and steering mechanism, having means for discharging an air jet 25 under directive control of said gyroscope, comprising an upwardly directed nozzle carried by the outer ring of the gyroscope, deflecting means consisting of a plate overlying the gyroscope having oppositely inclined 30 orifices in circular order to receive the jet, and jet-actuated means overlying such plate to receive the deflected jets from such orifices and connected to control the steering mechanism.
- 35 7. A gyroscopic steering apparatus comprising a gyroscope and steering mechanism, having means for discharging an air jet under directive control of said gyroscope, deflecting means comprising a plate overlying 40 the gyroscope having oppositely inclined orifices, a fan overlying such deflecting means, and a stationary support above said fan having a central bearing, a vertical shaft turning in said bearing carrying said fan, 45 and an operative connection between the upper end of said shaft and the steering mechanism.
8. A gyroscopic steering apparatus comprising a gyroscope and steering mechanism, 50 having means for discharging an air jet under directive control of said gyroscope, jet-actuated means operated by said jet, intervening deflecting means having oppositely inclined jet deflecting surfaces, an operative 55 connection between said jet-actuated means and the steering mechanism, and means for limiting its action to the normal controlling movement.
- 60 9. A gyroscopic steering apparatus comprising a gyroscope and steering mechanism, having means for discharging an air jet under directive control of said gyroscope, jet-actuated means operated by said jet, intervening deflecting means having 65 oppositely inclined jet deflecting surfaces, and

an operative connection between such jet-actuated means and the steering mechanism adapted to reverse the action of the latter by a movement approximating one-half revolution of the jet-actuated means.

10. A gyroscopic steering apparatus comprising a gyroscope, means for discharging an air jet controlled thereby, deflecting means adapted to receive such jet, a fan rotatable around the vertical axis of the 75 gyroscope, a steering engine, and an operative connection between such fan and the valve of such engine, adapted to impart the extreme reverse movement to such valve by a one-half turn of the fan, and having 80 means for limiting the movement thereto.

11. A gyroscopic steering apparatus comprising a gyroscope, means for discharging an air jet controlled thereby, deflecting means adapted to receive such jet, a fan 85 rotatable around the vertical axis of the gyroscope, a steering engine, a crank turned by said fan, a connection from said crank to the valve of said engine, and stop means in connection therewith for limiting the 90 movement to approximately a half turn of said crank.

12. In a torpedo, a gyroscopic steering apparatus comprising a gyroscope and steering mechanism, having means for discharging an air jet under directive control of said gyroscope, jet-actuated means arranged to be operated by said jet in all positions of the gyroscope and controlling said steering mechanism, and means associated therewith adjustable angularly in a horizontal plane for determining the angular course of the 100 torpedo.

13. In a torpedo, a gyroscopic steering apparatus comprising a gyroscope and steering mechanism, having means for discharging an air jet under directive control of said gyroscope, jet-actuated means operated by said jet and controlling said steering mechanism, and intervening deflecting means adjustable around the vertical axis of the 105 gyroscope whereby to determine the angular course of the torpedo.

14. In a torpedo, a gyroscopic steering apparatus comprising a gyroscope and steering mechanism, having means for discharging an air jet under directive control of said gyroscope, jet-actuated means operated by said jet and controlling said steering mechanism, and intervening deflecting means comprising a circular disk having a succession of oppositely inclined jet deflecting surfaces, and means for turning said disk around the vertical axis of the gyroscope to determine the angular course of the 115 torpedo.

15. A gyroscopic steering apparatus comprising a gyroscope and steering mechanism, means for discharging an air jet under directive control of said gyroscope, deflecting 120

means adjustable around the vertical axis of the gyroscope, jet-actuated means, and adjusting means for turning said deflecting means to determine the angular course of the torpedo.

16. A gyroscopic steering apparatus comprising a gyroscope and steering mechanism, means for discharging an air jet under directive control of said gyroscope, a disk 10 mounted to turn around the vertical axis of the gyroscope carrying at its center one of the pivotal bearings of the gyroscope and having successive oppositely inclined

orifices for deflecting said jet, jet-actuated means operated by the deflected jet and controlling said steering mechanism, and means for turning said disk for determining the angular course of the torpedo. 15

In witness whereof, I have hereunto signed my name in the presence of two sub- 20 scribing witnesses.

FRANK M. LEAVITT.
